(57) **CLAIM**

The ornamental design for a patient monitor, as shown and described.

DESCRIPTION

FIG. 1 is a perspective view showing a new design for a patient monitor;

FIG. 2 is a side view thereof;

FIG. 3 is a side view thereof opposite the side view of FIG. 2;

FIG. 4 is a front view thereof;

FIG. 5 is a rear view thereof;

FIG. 6 is a top view thereof; and,

FIG. 7 is a bottom view thereof.

The broken lines are included for the purpose of illustrating portions of the patient monitor that form no part of the claimed design.
